UNITED STATES PATENT OFFICE.

ELIZABETH A. ROBINSON, OF SCRANTON, PENNSYLVANIA.

VENTILATING APPARATUS FOR PULLMAN CARS.

Application filed February 25, 1922. Serial No. 539,193.

To all whom it may concern:

Be it known that I, ELIZABETH A. ROBINSON, a citizen of the United States, residing at Scranton, in the county of Lackawanna and State of Pennsylvania, have invented certain new and useful Improvements in Ventilating Apparatus for Pullman Cars, of which the following is a specification, reference being had to the accompanying drawings.

This invention relates to ventilating apparatus for Pullmans and has for an important object thereof the provision of means whereby the ventilation of the berths may be controlled to suit the wishes of the occupant thereof.

A further object of the invention is to provide a device of this character which may be readily operated by the occupant of the berth.

A still further object of the invention is to provide a device of this character which will add to rather than detract from the appearance of the car in which it is employed.

A still further object is to provide a novel construction of ventilator cowl whereby the air will be forced in at the ventilator openings regardless of the direction of motion of the train.

Other objects and advantages of the invention will become apparent throughout the course of the following description.

In the accompanying drawings wherein for the purpose of illustration is shown a preferred embodiment of my invention and wherein like reference characters designate like parts throughout:

Figure 1 is a fragmentary sectional view taken through a Pullman berth showing a ventilating apparatus constructed in accordance with my invention;

Figure 2 is a section taken on the line 2-2 of Figure 1;

Figure 3 is a front elevation of the berth curtain ventilator;

Figure 4 is a front elevation of the ventilator cowl;

Figure 5 is a front elevation of the controlling device regulating the amount of incoming air; and

Figure 6 is a fragmentary detail view of the controlling device, parts being broken away.

Referring now more particularly to the drawings, the numeral 10 indicates the wall

of a Pullman car having formed therethrough, adjacent the upper end of the berth, an opening 11 in which is secured a cylinder 12 having its ends open.

Slidably mounted within the cylinder 12 is a ventilator regulator 13 comprising a cylinder having one end closed, as at 14, by an ornamental head plate disposed inferiorly of the car and provided in the side wall thereof with spaced rows of spaced openings 15, the openings of each row being of the same size and the openings of the different rows being of different sizes, the smallest openings being arranged nearest the closed end 14^a and the size of the openings of the rows increasing as the distance from the head increases. Secured to the regulator 13 is a spring 16 extending through a slot 13^a formed in the wall of the regulator and provided with indentations 17 corresponding in number and arranged about the rows of openings 15, these indentations being adapted for selective engagement with a stop pin 18 whereby the regulator is resiliently held in any desired adjusted position, the spring 16 yielding to permit movement of the regulator when desired. The regulator 13 and the cylinder 12 have coacting means preventing rotation of the regulator and limiting the movement of the regulator within the cylinder, this coacting means being indicated at 19 as a pin and slot engagement. It is further pointed out that the pin and slot engagement, including the pin 18, likewise serves to prevent rotation of the regulator 13 within the cylinder. It will thus be seen that the pin 18 serves as a single means carried by the tube and coacting with the regulator for limiting the sliding movement of the regulator preventing rotation of the regulator and for maintaining the regulator in adjusted positions at points intermediate the limit of its movement.

Secured to the exterior surface of the car as by means of an attaching flange 20 about the opening 11 is a ventilator cowl 21 of a construction such that it will, without shifting the regulator thereof, direct air into the open end of the cylinder 12 and regulator 13 regardless of the direction of movement of the train. In the present instance this is attained by the employment upon the cowl 21 of a depending flange 22 spaced from the side wall of the car, and a flange 23 upon the opposite side of the

cowl arranged adjacent the side of the car. When the train is moving in one direction the air passing between the flange 22 and the side of the car will abut the flange 23 and be directed into the opening. When moving in the other direction the air passing by the flange 23 will engage the flange 22 and be directed toward the opening, it being understood that the high rate of speed at which Pullman trains travel in the present day is sufficient to offset any counteracting air currents.

The numerals 24 and 25 indicate the berth curtains by means of which the occupant of the berth is shielded from the aisle, the curtain 25 being provided with the usual flap attachment 26. To this flap attachment, if the flap be arranged interiorly of the curtain, and to the curtain 25, if the flap be arranged exteriorly of the curtain, is secured, as by means of an attaching flange 27, a ventilating device 28. This device comprises a plate 29 adapted to face the aisle and having upon its outer face the indicia 29^a indicating the number of the berth to which it is applied. The plate 29 has an annular flange 30 upon which the securing flange 27 is formed and in this flange 30 are formed ventilator openings 31, the curtain 25 or curtain flap 26, as the case may be, being provided with an opening 26^a coinciding with the interior of the flange 30 so that the interior of the berth is in communication with the interior of the flange and accordingly air can move from the berth through the openings 31 into the aisle of the car and so pass out through the ventilators. The curtain 24 is provided with an opening 32 through which the ventilating apparatus 28 may be extended and the curtain 25 or flap 26, as the case may be, is likewise provided with an opening 33 through which the ventilating device extends. The exterior portion of the curtain 25 is provided with a plate 34 having an opening 35 formed therethrough through which may be extended a turn-button fastener 36 which is secured to the curtain 24 to secure the curtain in closed position and maintain the ventilating device with the openings thereof at the aisle side of the closed curtain.

In the use of my device when the occupant of the berth desires to increase or decrease the amount of air entering the berth from the exterior of the car this may be accomplished by shifting the regulator 13 either in or out, as the case may be. Moving the regulator inwardly exposes more openings interiorly of the car through which the air directed inwardly of the flanges 22 and 23 may pass and conversely moving the regulator outwardly decreases the number of openings exposed. The air passed from the ventilator openings passes through the berth

and out through the openings of the ventilator device 28 into the aisle of the car where it may pass out through the usual ventilators provided at the upper structure of the car, which form no portion of my invention and are accordingly not herein shown.

From the foregoing it is believed to be obvious that a ventilator apparatus constructed in accordance with my invention is particularly well adapted for the purpose for which it is intended by reason of the fact that it places the ventilation of each individual berth under the control of the occupant thereof and by reason of the fact that the method of adjustment and regulation is very simple in construction and may be very readily applied to the structure of Pullman cars now in use. It will furthermore be obvious that the specific example of my invention hereinbefore set forth is capable of many changes and modifications without in any manner departing from the spirit of my invention and I accordingly do not limit myself to such specific structure except as hereinafter claimed.

I claim:

1. In a vehicle ventilator, the combination with a side wall of the vehicle having an opening formed therein, of a tube mounted within the opening, a regulator mounted within the tube for controlling the passage of air therethrough, and means stationary with respect to the vehicle wall disposed exteriorly of the vehicle, including a deflector directing air into the opening during movement of the vehicle in one direction, and a second deflector directing air into the opening during movement of the vehicle in the opposite direction.

2. In a vehicle ventilator, the combination with a vehicle wall having an opening formed therein, of a tube mounted within the opening, a regulator having a closed inner end slidably mounted within the tube and having openings therein spaced longitudinally thereof, means disposed exteriorly of the vehicle for directing a current of air into the opening, and means for locking said regulator in adjusted positions including a spring carried by said regulator and having indentations, and a pin carried by said tube and engaging said indentations.

3. In a vehicle ventilator, the combination with a vehicle wall having an opening formed therein, of a tube mounted within the opening, a regulator having a closed inner end and perforated side walls slidable within the tube, and a single means carried by the tube and coacting with the regulator limiting the sliding movement thereof, preventing rotation thereof and maintaining the regulator in adjusted position at points intermediate the limits of its movement.

4. In a ventilator, the combination with a tube adapted to be inserted in an opening in

the wall, of a regulator having a closed inner end slidably mounted within the tube and constructed to permit the passage of air through said tube in increased amounts as it is drawn from the tube, said regulator fitting within the tube and having formed in a wall thereof a longitudinally extending slot, a pin carried by the tube and engaging in said slot, and a spring secured to the regulator wall and having indentations with which said pin engages.

5. In a Pullman ventilator, the combination with a car wall having an opening formed therein, of a tube mounted within 15 the opening, a regulator having a closed inner end slidably mounted within the tube and having openings therein spaced longitudinally thereof, means disposed exteriorly of the car for directing a current of air into 20 the opening, said regulator having openings formed therein, and yieldable means carried by the regulator and coacting with a fixed member carried by the tube for locking the regulator in adjusted position, said 25 fixed member operating in the slot in the regulator.

6. The combination with a side wall of a vehicle having an opening formed therein

and a regulator mounted in said opening to control the amount of air passing therethrough to the interior of the car, of a cowl secured to the exterior surface of the vehicle at said opening and embodying a pair of flanges, one of said flanges directing the air into said opening during movement of the vehicle in one direction and the other of said flanges directing air into said opening during movement of the vehicle in the opposite direction.

7. The combination with a vehicle having an opening formed in the side wall thereof and a regulator disposed in said opening and controlling the amount of air passing therethrough into the interior of the vehicle, of a cowl secured to the exterior surface of the vehicle above the opening and provided with a pair of depending flanges spaced longitudinally of the vehicle, one of which is arranged adjacent the side of the car, the other of said flanges being spaced from the side of the vehicle a distance equal to the width of the first named flange.

In testimony whereof I hereunto affix my signature.

ELIZABETH A. ROBINSON.
